UNITED STATES PATENT OFFICE.

JOHN T. RICHARDSON, OF HARRISBURG, ASSIGNOR OF ONE-HALF TO
ALEXANDER H. EGE, OF MECHANICSBURG, PENNSYLVANIA.

RAILWAY-FROG.

SPECIFICATION forming part of Letters Patent No. 328,810, dated October 20, 1885.

Application filed August 21, 1885. Serial No. 174,986. (No model.)

To all whom it may concern:

Be it known that I, JOHN T. RICHARDSON, of Harrisburg, county of Dauphin and State of Pennsylvania, have invented certain new and useful Improvements in Railway-Frogs, of which the following is a specification.

The object of my invention is to construct a frog that shall combine simplicity and flexibility of structure with durability and efficiency in the performance of its required functions, an end that I attain by the use of clamping-bars, distance or filling blocks, wedges, and bolts, as hereinafter described, and illustrated in the accompanying drawings.

15 In referring to the drawings, Figure 1 shows a plan view of my improved frog. Fig. 2 is a transverse section on line *xx* of Fig. 1, taken through the longest clamp longitudinally. Fig. 3 is a section on line *yy* of Fig. 1, taken 20 through the shorter clamp; Figs. 4 and 5, detached views on an enlarged scale.

A A are the outer curved or wing-rails of the frog, and B B the inner rails converging to and terminating in the point or tongue *b* 25 of the frog. The rails constituting the frog rest upon clamping-bars C, of which at least two are used in each structure. Said clamping-bars terminate in flanges *c c*, that are turned upward to a degree more or less vertical, as shown in Fig. 4. The terminal flanges of the clamps are perforated at a point about equidistant from the angles of the base to the ends of the flanges, for a purpose hereinafter more fully set forth. Wedge-shaped blocks 30 or keys D D are interposed between the flanges of the clamping-bars and the outer surface of the webs *d* of the wing-rails, as shown. Said keys D are more or less plano-convex throughout their entire length, and slotted longitudinally for the reception of the binding-bolts *e e*.

By this construction the keys admit of having their convex sides fitted into the shanks or longitudinal depressions on the outer sides of the wing-rail A, and their plane sides in close 45 contact with the vertical inner surfaces of the clamping-bars. In line with the slotted perforations of the keys, when in position, the webs of the wing-rails A are also perforated for the reception of the binding-bolts *e e*.

50 Upon the vertical edges of the filling-blocks

g g, as shown in Fig. 5, interposed between the outer and inner rails of the frog, depressions or rabbeted seats are wrought, and into these seats the nuts *i* rest when the binding-bolts *e* are in place.

To bind the co-operating parts of the frog together, the bolts *e* upon each side of the frog are passed through the perforations of the upturned flanges of the clamping-bars C, the slot *a* of the keys D, the contiguous perforation through the webs of the wing-rails A, and the nuts in the rabbeted seats *i* of the filling-blocks *f*, as shown in Fig. 4. The bolts *e* are then driven home by means of an ordinary wrench or similar appliance, the vertical 60 shoulders of the rabbeted seat *g* meanwhile performing the function of a nut-lock to prevent the revolution of the nuts *i* during the operation or subsequent thereto.

In considering, further, the use of the binding-bolts *e e*, it is evident that they not only prevent the slipping forward and backward of the clamping-bars, wedges, and filling-blocks, but they also perform, in addition, the very important function of preventing the 70 flanges of the clamping-bars being bent outwardly under the excessive blows of the sledge-hammer in driving forward the keys that may subsequently become necessary to take up the slack that in time is occasioned by the constant abrasion of the constituent parts of the frog in contact. In this way, by a very simple device, I am able most successfully to overcome one of the most vital imperfections that has attached to the different forms of clamp- 75 frogs heretofore in general use.

I am aware that a bolt vertically placed in connection with a slotted key and clamping-bar has been used, and hence I do not claim this combination, broadly; but I do claim that 80 the use of a bolt passing horizontally through the flanges of the clamping-bars, the slotted keys, the webs of the contiguous wing-rails, and terminated at this point by a nut resting in a depression or seat of the adjacent block-filling, is new.

Having thus described my invention, what I claim is—

1. The combination, with the rails and distance-pieces of a frog, of the clamping-plates 85

C, and wedges D, and the laterally-piercing binding-bolts e, substantially as described.

2. The combination of the laterally-pierced flanges of the clamping-plates C, plano-convex and longitudinally-slotted wedges D, the perforated wing-rails A, and the laterally-rabbeted block-fillings or distance-pieces f, as and for the purpose set forth.

In testimony whereof I have signed my name to this specification in the presence of two sub-
scribing witnesses.

JOHN T. RICHARDSON.
